UNITED STATES PATENT OFFICE

HARRY F. WANAMAKER, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA

STRIPPING MECHANISM FOR HOSIERY DRIERS

Application filed February 6, 1931. Serial No. 513,977.

This invention relates to means for loosening the top portion of a stocking relative to the form on which the stocking has been tautly drawn as a result of its having been dried on the form, as, in an automatic hosiery drier such as that shown and described in U. S. Letters Patent No. 1,126,619, dated January 26, 1915, the loosening or stripping of the top of the stocking being effected prior to the complete removal of the stocking from the form by an automatically operated means such as that shown and described in the patent noted.

The present invention constitutes an improvement over the top stripping mechanism shown and described in U. S. Letters Patent No. 1,711,334, dated April 30, 1929.

In the device shown and described in the last-mentioned patent the stripping or loosening of the top of a stocking is effected after the stocking form has been moved from the normal vertical position, in which it was held during its passage through the drier, to the horizontal position assumed by the form for the purpose of automatic removal of the stocking from the form, by the above-mentioned mechanism shown in the first-mentioned patent.

In the last-mentioned patent the loosening or stripping of the top is effected by contact of the loosening means with but one face of the form and the one side of the stocking adjacent thereto.

The primary object of the present invention is to provide a loosening or stripping mechanism which shall make contact with both sides of the form and the oppositely disposed sides of the stocking adjacent the opposite sides of the form respectively, in order to eliminate undue strain on the stocking fabric which, in the finer grades of stocking, has a tendency to stretch the one side of the stocking out of shape with respect to the opposite side of the stocking, such as occasionally happens when contact of the stripping mechanism is made with but one side of the stocking and the underlying form.

Another object of the invention is to construct the stripping mechanism in such a manner that the pressure of the stripping

mechanism against the form and the stocking carried thereby may be minutely regulated, so as to reduce the friction between the stocking and the form during the loosening operation when a relative movement between the form and the stocking is effected.

Another object of the invention is to loosen the top of the stocking with respect to the form while the form is still in its normal vertical position, in order to make contact with both sides of the form simultaneously and to simplify the construction of the stripping mechanism, the construction and operation of which will be fully disclosed herein-after, reference being had to the accompanying drawings, of which:

Fig. 1 is a front elevation of an automatic hosiery drier with the improved stripping mechanism applied thereto;

Fig. 2 is an end elevation of the drier shown in Fig. 1;

Fig. 3 is a plan view of the drier shown in Figs. 1 and 2;

Fig. 4 is a front elevation of the stripping mechanism shown in Fig. 1, detached and drawn to an enlarged scale, and showing the stripping mechanism in an inoperative position;

Fig. 5 is a view similar to Fig. 4, but showing the stripping mechanism in its operative position; and

Fig. 6 is a side elevation of the stripping mechanism and the means for actuating the same in timed relation to the form conveying means of the drier.

As shown in Figs. 1, 2 and 3, the drier comprises a track or frame 1 adapted to support and guide a plurality of stocking forms 2, the forms 2 being supported on and moved around the track or frame 1 by mechanism, such as that shown and described in the first-mentioned Letters Patent No. 1,126,619, which forms no part of the present invention.

The drier also comprises a drying chamber 3 which overhangs one side of the track 1 to enclose the stocking forms 2 as they pass along that particular part of the track, the forms entering the drying chamber 3 through a slot 4 formed at one side of the housing that constitutes the drying chamber 3 and emerg-

ing from the opposite side of the drying chamber, while in a vertical plane, through a similar slot 5.

As the stocking forms 2 move out of the drying chamber 3 through the opening 5 they are automatically operated upon by the top stripping mechanism 10. This stripping mechanism comprises a pair of brackets 11, 11 secured to opposite sides of the portion of the track 1 along which the forms 2 pass as they emerge from the drying chamber 3. Rigidly secured in each of the brackets 11 is a vertically extending guide post 12. Slidably mounted on the upper portion of each of the posts 12 is a gripper carriage 13, comprising a sleeve portion 14 which is adapted to slide vertically on the post 12. Pivotaly mounted at 15 to the upper portion of each carriage 13 is an arm 16, to the outer end 20 of which is pivotally mounted, at 17, a gripper or shoe 18, having a serrated surface 19.

The serrated surfaces 19, 19 of the shoes 18, 18 disposed respectively at opposite sides of the centrally located form 2 are adapted to be moved from the inoperative position shown in Fig. 4 to the operative positions shown in Fig. 5, in engagement with the oppositely disposed flat faces 2a, 2a of the form 2, in direct opposition to each other, in order that the stocking α on the form 2 will be engaged at directly opposite points on its respective sides.

Movement of the gripping shoes 18, 18 from their inoperative positions, shown in Fig. 4, to their operative positions, shown in Fig. 5, is effected by links 20, 20 pivotally connected at one end, to the levers or arms 16, intermediate the ends of the said arms, as indicated at 21, the opposite end of each link 20 being pivotally connected, as at 22, to a lateral extension 23 of a collar 24, which is slidably mounted on the sleeve portion 14 of the gripper carriage 13.

Relative movement of the slider 24, longitudinally of the sleeve 14, is limited by a pair of spaced adjustable collars 25 and 26, the lower collar 25 limiting the movement of the shoes 18 away from the form 2, while the upper collar 26 limits the movement of the shoes 18 toward the form 2, and by adjustment of the collars 25, 26 longitudinally of the sleeves 14, 14 the degree of pressure exerted by the shoes 18, 18 on the opposite sides of the form 2 may be minutely controlled.

Below the lower end of each of the gripper carriages 13 is provided, on the uprights 12, a laterally extending bearing 27 for slidably supporting one end of an operating rod 28, the upper end of which is rigidly connected to the lateral extension 23 of the slider 24, while the opposite or lower end of each of the operating rods 28 is rigidly connected to a cross bar 29, the rods 28, 28 being slidably guided intermediate their ends by bearings 30, 30 carried by or formed as integral parts

of the brackets 11, 11, in the present instance.

Substantially at the center of the connecting cross bar 29 is a bearing 31, to which is pivotally connected, at 32, one end of a link 33, the opposite end of which is pivotally connected, at 34, to one end 35 of a lever 36. The lever 36 is mounted on a shaft 37, rotatably carried in brackets 38 mounted on the framework 1a of the drier. A second lever 39 is secured to the shaft 37 and lies under one end 40 of an arm 41 of a bell-crank lever 42, which is pivoted at 43 to a bracket 44 carried by the framework 1a.

The outer end 45 of the second arm 46 of the bell-crank lever 42 extends into the path of a roller 47 which is rotatably mounted on and extends laterally from a disc 48 that is carried by a shaft 49, which may be one of the shafts that supports and drives the conveyer screw 51 that moves the forms along the track or frame 1, or the shaft 49 may be independently mounted in the framework and geared to the conveyer screw shafts, such as those shown in U. S. Letters Patent No. 1,126,619, in order that the operation of the stripping mechanism 10 will be so timed with respect to the conveying screws as to effect operation of the stripping mechanism at the time each of the forms 2 emerges from the slot 5 of the drying chamber 3.

In operation the elements of the stripping mechanism 10 normally occupy the positions shown in Fig. 4. As a form 2 emerges from the drying chamber the bell-crank lever 42 is engaged by the roller 47, which in turn rocks the lever 36 about its pivot and raises the operating rods 28, 28. Initial upward movement of the rods 28 effects a relative sliding movement between the sliders 24 and the sleeves 14 which, through the links 20, rocks the levers 16 about their pivots 15, thereby moving the shoes 18, 18 from the normal position shown in Fig. 4 to the broken line position shown in Fig. 5, at which time the upper sides of the sliders 24 come into contact with the undersides of the collars 26; thus, minutely controlling the degree of pressure exerted by the shoes 18 against the fabric of the stocking lying adjacent the opposite flat sides of the stocking form 2.

Continued elevation of the operating rods 28 will raise the carriages 13, 13 on the supporting standards 12, 12, consequently moving the arms 16, 16 and the shoes 18, 18 carried thereby bodily upward with respect to the stationary form 2 and in so doing slides the top portion α^1 of the stocking α upwardly on the form 2 toward the foot portion thereof, which loosens the top α^1 of the stocking α from the broader lower portion of the stocking form 2, as the form 2 is held in the vertical position.

Continued rotation of the shaft 49 causes the roller 47 to ride off the end 45 of the bell-crank lever 42, permitting the elements of

the stripping device 10 to return to their normal positions shown in Fig. 4.

The stocking form 2 with the loosened stocking thereon then advances along the 5 track or frame 1 and by mechanism forming no part of the present invention the form is turned from its vertical position to a horizontal position wherein the heel and toe portions of the stocking form with the stocking 10 thereon are gripped by the removing mechanism 50 (see Fig. 3), so that as the form is moved further along the frame 1, in a direction substantially at right angles to its former direction of movement which caused 15 the form to emerge from the drying chamber 3 the toe and heel portions of the stocking will be held rigidly by the gripping mechanism 50 while the stocking form is drawn out of the stocking in the manner disclosed in 20 U. S. Letters Patent No. 1,126,619.

From the above, it will be seen that the stripping mechanism 10 by loosening the top portion α^1 of the stocking α relative to the stocking form 2 prior to the gripping of the 25 stocking by the mechanism 50 facilitates the removal of the stocking from the form and relieves the stocking fabric of the strain to which it would be otherwise subjected if no loosening of the top were effected and the 30 entire removal of the stocking from the form was effected by the gripping mechanism 50 alone.

From the above, it will be obvious that the 35 stocking fabric by being gripped at both sides of the form simultaneously and with equalized pressure is relieved of any strains, such as would be effected by contact of the stripping mechanism with one side of the stocking and the underlying form which would cause the opposite side of the stocking 40 to drag on the stocking form.

I claim:

1. A device for loosening the top of a 45 stocking from a form on which the stocking is tautly disposed, comprising means for gripping the stocking at directly opposed points on opposite sides of the form intermediate the top and foot of the stocking and moving the top toward the foot and relative to the form, and means for regulating the degree of pressure exerted by the gripping 50 means at the opposite sides of the form respectively to equalize the actions of the gripping means at said opposite sides of the form.

2. A device for loosening the top of a 55 stocking from a form on which the stocking is tautly disposed, comprising means for gripping the stocking at directly opposed points on opposite sides of the form intermediate the top and foot of the stocking and moving the top toward the foot and relative to the form, and means for independently 60 regulating the degree of pressure exerted by 65 the gripping means at each of the opposite

sides of the form to equalize the actions of the gripping means at said opposite sides of the form.

3. A device for loosening the top of a 70 stocking from a form on which the stocking is tautly disposed, comprising a pair of grippers disposed at opposite sides of the form respectively, means for moving said grippers into gripping contact with the portions of the stocking adjacent the said opposite sides of the form, and means for moving said grippers substantially parallel to the plane of the form to move the stocking top toward the foot portion thereof and relative to the form. 75

4. A device for loosening the top of a 80 stocking from a form on which the stocking is tautly disposed, comprising a pair of grippers disposed at opposite sides of the form respectively, guiding means for each 85 gripper, means for moving the grippers laterally with respect to their guideways into gripping contact with the stocking on the form, and means for moving the grippers longitudinally of their guideways to move the 90 top of the stocking toward the foot thereof and relative to the form.

5. A device for loosening the top of a 95 stocking from a form on which the stocking is tautly disposed, comprising a pair of grippers disposed at opposite sides of the form respectively, a guide for each gripper, a carriage slidably mounted on each guideway, means for pivotally connecting the grippers to the carriages, and means for 100 turning the grippers about their pivots on the carriages for contacting of the grippers with the stocking on the form and for moving the grippers and their carriages longitudinally of the form to move the top of the 105 stocking toward the foot thereof and relative to the form.

6. A device for loosening the top of a 110 stocking from a form on which the stocking is tautly disposed, comprising a pair of grippers disposed at opposite sides of the form respectively, a guide for each gripper, a carriage for each gripper slidably mounted on the guide, an arm pivotally mounted at one end to the carriage and carrying the 115 gripper at its opposite end, an operating rod 120 slideable longitudinally of the guide, and a link connecting the operating rod to the gripper carrying arm for swinging the gripper into contact with the stocking on the form and for moving the gripper longitudinally of the form to move the top of the 125 stocking toward the foot thereof and relative to the form upon a longitudinal movement of the operating rod.

7. A device for loosening the top of a 130 stocking from a form on which the stocking is tautly disposed, comprising a pair of grippers disposed at opposite sides of the form respectively, a guide for each gripper, 135

13 a carriage for each gripper slidably mounted on the guide, an arm pivotally mounted at one end to the carriage and carrying the gripper at its opposite end, an operating rod 18 slidably longitudinally of the guide, a link connecting the operating rod to the gripper carrying arm for swinging the gripper into contact with the stocking on the form and for moving the gripper longitudinally of the 23 form to move the top of the stocking toward the foot thereof and relative to the form upon a longitudinal movement of the operating rod, and means for effecting said longitudinal movement of the rod.

18 8. A device for loosening the top of a stocking from a form on which the stocking is 28 tautly disposed, comprising a pair of grippers disposed at opposite sides of the form respectively, a guide for each gripper, a carriage for each gripper slidably mounted on the guide, an arm pivotally mounted at one end to the carriage and carrying the gripper at its opposite end, an operating rod 33 slidably longitudinally of the guide, a link connecting the operating rod to the gripper carrying arm for swinging the gripper into contact with the stocking on the form and for moving the gripper longitudinally of the form to move the top of the stocking toward the foot 38 thereof and relative to the form upon a longitudinal movement of the operating rod, means for effecting said longitudinal movement of the rod, comprising a lever operatively connected to said rod, and means for 43 rocking said lever.

48 9. A device for loosening the top of a stocking from a form on which the stocking is 53 tautly disposed, comprising a pair of grippers disposed at opposite sides of the form respectively, a guide for each gripper, a carriage for each gripper slidably mounted on the guide, an arm pivotally mounted at one end to the carriage and carrying the gripper at its opposite end, an operating rod 58 slidably longitudinally of the guide, a link connecting the operating rod to the gripper carrying arm for swinging the gripper into contact with the stocking on the form and for moving the gripper longitudinally of the 63 form to move the top of the stocking toward the foot thereof and relative to the form upon a longitudinal movement of the operating rod, means for effecting said longitudinal movement of the rod, comprising a constant 68ly rotating element, and means operatively connected to the rod and adapted to be intermittently engaged by said rotating element for reciprocating said rod relative to said guide.

73 10. A device for loosening the top of a stocking from a form on which the stocking is 78 tautly disposed, comprising a pair of grippers disposed at opposite sides of the form respectively, a guide for each gripper, a carriage 83 slidably mounted on the guide, an arm

pivoted to the carriage and supporting said gripper at its free end, a slider element slidably mounted in the carriage, a link pivoted at one end to the gripper and at its opposite end to said slider, means for moving the slider relative to the carriage to bring the gripper into contact with the stocking on the form, and means for moving the carriage longitudinally of the form to cause the gripper to move the top of the stocking toward the foot thereof and relative to the form.

80 11. A device for loosening the top of a stocking from a form on which the stocking is 85 tautly disposed, comprising a pair of grippers disposed at opposite sides of the form respectively, a guide for each gripper, a carriage 90 slidably mounted on the guide, an arm pivoted to the carriage and supporting said gripper at its free end, a slider element slidably mounted in the carriage, a link pivoted at one end to the gripper and at its opposite end to said slider, means for moving the slider relative to the carriage to bring the gripper into contact with the stocking on the form, means for regulating the amount of relative movement between the slider and the carriage to control the degree of pressure exerted by the gripper on the stocking, and means for moving the carriage longitudinally of the form to cause the gripper to move the top of the stocking toward the foot thereof and relative to the form.

95 12. A device for loosening the top of a stocking from a form on which the stocking is 100 tautly disposed, comprising a pair of grippers disposed at opposite sides of the form respectively, a guide for each gripper, a carriage 105 slidably mounted on the guide, an arm pivoted to the carriage and supporting said gripper at its free end, a slider element slidably mounted in the carriage, a link pivoted at one end to the gripper and at its opposite end to said slider, an operating element 110 operatively connected to said slider for moving the slider relative to the carriage to effect contact between the gripper and the stocking on the form and for subsequently moving the carriage and the gripper longitudinally of the form to move the top of the stocking toward the foot thereof and relative to the form.

115 13. A device for loosening the top of a stocking from a form on which the stocking is 120 tautly disposed, comprising a pair of grippers disposed at opposite sides of the form respectively, a guide for each gripper, a carriage 125 slidably mounted on the guide, an arm pivoted to the carriage and supporting said gripper at its free end, a slider element slidably mounted in the carriage, a link pivoted at one end to the gripper and at its opposite end to said slider, an operating element 130 operatively connected to said slider for moving the slider relative to the carriage to effect contact between the gripper and the stocking.

on the form and for subsequently moving the carriage and the gripper longitudinally of the form to move the top of the stocking toward the foot thereof and relative to the form, and a stop for limiting the relative movement between the slider and the carriage for regulating the degree of pressure exerted by the gripper on the stocking.
